(57) **CLAIM**

The ornamental design for a container for food, as shown and described.

DESCRIPTION

FIG. 1 is a front elevational view of a container for food showing my new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a top, right, and front perspective view thereof; and,

FIG. 8 is an exploded view of FIG. 7.

The broken lines in the drawings depict portion of the container for food that form no part of the claimed design.
